UNITED STATES PATENT OFFICE.

DANIEL W. SMITH, OF CHICAGO, ILLINOIS, ASSIGNOR TO INTERNATIONAL HARVESTER COMPANY, A CORPORATION OF NEW JERSEY.

SHEAF-CARRIER ATTACHMENT.

No. 797,236.

Specification of Letters Patent.

Patented Aug. 15, 1905.

Application filed March 3, 1905. Serial No. 248,259.

To all whom it may concern:

Be it known that I, DANIEL W. SMITH, a citizen of the United States, residing at Chicago, in the county of Cook and State of Illinois, have invented certain new and useful Improvements in Sheaf-Carrier Attachments, of which the following is a specification, reference being had to the accompanying drawings, forming a part thereof.

My invention relates to sheaf-carrier attachments for grain-harvesters; and it is particularly designed for use in connection with attachments of the above character having endless-apron carriers operative to deliver the sheaves therefrom, the object of the invention being to provide means for retaining the sheaves upon the carrier and preventing their premature delivery therefrom until by the regular operation of the carrier they are deposited upon the ground.

My invention consists in providing an end-gate that is pivoted on the frame of the carrier and operates to close the delivery end thereof while it is receiving its load and which is released and allowed to swing outward as soon as the endless carrier begins its movement to discharge the accumulated load.

Figure 1 represents a plan view of a harvesting-machine having a sheaf-carrier embodying my invention attached thereto. Fig. 2 represents a plan view of the carrier detached from the machine. Figs. 3, 4, 5, and 6 are views showing details of construction, and Figs. 7 and 8 represent details of the clutch mechanism.

The same reference-numerals denote like parts.

7 represents the main frame of the harvester, upon which the grain-receiving platform and cutting apparatus are mounted.

8 represents the push-pole, and 9 the platform upon which the operator stands.

10 represents the binder attachment, located at the delivery end of the carriers and adapted to deliver the bound sheaves stubbleward therefrom.

11 represents a sheaf-carrier frame, suitably supported at the delivery side of the binder attachment, and 12 represents an endless carrier mounted upon suitable driving and driven rollers that are journaled in said carrier-frame.

The endless carrier is given motion through its connection with a moving part of the har-

vester mechanism and is caused to move intermittently by any of the well-known means commonly used to produce such result. In the form as shown the part 13 is continuously driven by means of the chain 14, and a clutch mechanism that is thrown into action by a movement of the lever 15 connects the driving-roller of the carrier with the continuously-driven member in any of the well-known ways. The carrier is tripped into intermittent movement to discharge the load by the operator pressing with his foot upon the trip-lever 16, mounted upon the platform 9. The trip-lever is connected, by means of a link 17, with a bell-crank lever 18, mounted upon the harvester-frame and connected with the clutch-shipping lever 15 by means of the link 19.

Pivoted upon the outer front corner of the sheaf-carrier frame is an end-gate 20, which is normally held closed across the delivery end of the carrier by means of a spring 21 coiled about its pivot and arranged to operate to close said gate. A short crank-arm 22 forms part of the end-gate connections, and 23 is a link pivotally connected to said crank and extending along the front of the carrier-frame is supported near its opposite end in a yielding manner by means of the spring-loop 24. A hook portion 25 is formed on the link that is adapted to engage with a fixed part of the carrier-frame, as shown in Fig. 6, in a manner to hold the said end-gate closed. The link 23 is extended inward beyond its hooked portion, and 25' is a rock-shaft suitably supported by the side bars of the carrier-frame, having the crank portion 26 adapted to engage with the link 23 in a manner to cause its hooked portion to be disengaged from the fixed part when said rock-shaft is turned in one direction, as shown in Fig. 4. At its opposite end said rock-shaft 25 is provided with a crank portion adapted to engage with the clutch-shipping lever 15 and be moved thereby to rock said shaft in its bearings and cause it to release the end-gate.

The end-gate is caused to open by the pressure of the load of bundles during the discharge operation of the carrier, and it is immediately closed by the action of the spring mechanism when the discharge of the load is effected. The tripping mechanism is caused to return to its initial position by means of a spring under the foot-lever 16.

The clutch mechanism comprises the con-

tinuously-rotating sprocket-wheel 13, having a clutch-tooth 28 on its inner surface that is adapted to engage with a roller 29, mounted on one end of a vibratile lever 30, that is pivotally mounted near its middle portion upon a part 31, secured to the shaft 32, that is connected with the driving-roller of the carrier. A coiled spring 33, operative between the opposite end of lever 30 and the part 31, normally holds the roller 29 from contacting with the tooth 28. Upon the end of shaft 32 is a longitudinally-movable sleeve 34, having a slot 35, through which projects a pin 36, that allows the sleeve to have a limited longitudinal movement on the shaft. The lever 15 has one arm bearing against the sleeve, and 37 is a coiled spring operative between the end of the shaft and the sleeve in a manner to press the sleeve against the lever. At the opposite end of the sleeve is a projecting arm 38, having an inclined portion 39 adapted to engage with the lever 30 in a manner to force it inward, and thereby cause the roller 29 to come within the path of the tooth 28, and thus clutch with the continuously-driven sprocket-wheel in a well-known way.

What I claim as my invention, and desire to secure by Letters Patent, is—

1. In a sheaf-carrier, the combination of a carrier-frame, an end-gate mounted to turn about a vertical pivot at the front and stubbleward corner of said frame, means for closing said gate across the delivery end of said carrier, means for locking said gate in its closed position, and means for releasing said locking means.

2. In a sheaf-carrier, the combination of a carrier-frame, an end-gate mounted to turn about a vertical pivot at the front and stubbleward corner of said frame, a spring operative to close said gate across the delivery end of said carrier, means for locking said gate in its closed position, and means for releasing said locking means.

3. In a sheaf-carrier, the combination of a carrier-frame, an endless carrier mounted upon said frame, means for intermittently operating said carrier, an end-gate mounted to turn about a vertical pivot at the front and stubbleward corner of said frame and means for normally locking it in a closed position across the delivery end of said carrier, and means connected with said intermittently-operating means for releasing said locking means.

4. In a sheaf-carrier, the combination of a carrier-frame, an endless carrier mounted upon said frame, a continuously-moving member adapted to operate said endless carrier, clutch mechanism adapted to connect said continuously-moving member with said endless carrier, a clutch-shipping lever operative to cause engagement of said clutch mechanism, an end-gate mounted to turn about a vertical pivot at the front and stubbleward corner of

said carrier-frame and operative to normally close the delivery end of said endless carrier, means for locking said gate in a closed position, and means operated by said shipping-lever for releasing said locking means.

5. In a sheaf-carrier, the combination of a carrier-frame, an endless carrier mounted upon said carrier-frame, a continuously-moving member adapted to operate said endless carrier, clutch mechanism adapted to connect said continuously-moving member with said endless carrier, a clutch-shipping lever operative to cause engagement of said clutch mechanism, an end-gate pivotally mounted on the carrier-frame, a spring adapted to close said gate across the delivery end of the carrier, means for locking said gate in its closed position, and means operated by said clutch-shipping lever for releasing said locking means.

6. In a sheaf-carrier, the combination of a carrier-frame, an endless carrier mounted upon said carrier-frame, means for intermittently operating said endless carrier, comprising a clutch mechanism and a clutch-shipping lever, an end-gate pivotally mounted on the carrier-frame and adapted to close the delivery end thereof, means for holding said gate closed, comprising a crank-arm connected with the gate and moving about its pivotal connection, a sliding bar pivotally connected with said crank-arm and having a hook engaging with a fixed part of the frame to lock it against movement when the gate is closed, and means operated by said clutch-shipping lever for releasing said locking means.

7. In a sheaf-carrier, the combination of a carrier-frame, an endless carrier mounted upon said carrier-frame, means for intermittently operating said endless carrier, comprising a clutch mechanism and a clutch-shipping lever, an end-gate pivotally mounted on the carrier-frame and adapted to close the delivery end thereof, means for holding said gate closed, comprising a crank-arm connected with the gate and moving about its pivotal connection, a sliding latch-bar pivotally connected with said crank-arm and engaging with a fixed part of the frame to lock said gate closed, a double crank-shaft mounted in the carrier-frame and having one crank-arm adapted to contact with said clutch-shipping lever and the other with said latch-bar in a manner to release said latch-bar when said clutch-shipping lever is operated in one direction, and means for operating said clutch-shipping lever.

8. In a sheaf-carrier, the combination of a carrier-frame, an endless carrier mounted upon said carrier-frame, means for intermittently operating said endless carrier, comprising a clutch mechanism and a clutch-shipping lever, an end-gate pivotally mounted on the carrier-frame and adapted to close the delivery end thereof, a coiled spring inclosing said pivotal connection and operative to close said

gate, means for holding said gate closed, comprising a crank-arm adapted to turn with the gate about its pivot, a latch-bar pivotally connected with said crank-arm and engaging a fixed part of the frame in a manner to lock said gate closed, a spring operative to hold said latch-bar in engagement with said fixed part, a rock-shaft mounted on the carrier-frame, crank-arms upon opposite ends of said rock-shaft, one of said crank-arms engaging

with said latch-bar and the other with said clutch-shipping lever, and means controlled by the operator for moving said clutch-shipping lever.

In witness whereof I hereto affix my signature in presence of two witnesses.

DANIEL W. SMITH.
